his ATTORNEY.

UNITED STATES PATENT OFFICE

WILLIAM DUBILIER, OF NEW YORK, N. Y., ASSIGNOR TO DUBILIER CONDENSER CORPORATION, A CORPORATION OF DELAWARE

CONDENSER

Application filed February 12, 1924. Serial No. 692,327.

This invention appertains to improvements in condensers, especially condensers for use in electrical circuits.

An object of my invention is to provide a construction wherein a greater or smaller number of units, each comprising sheets or layers of conductive material separated by a dielectric, may be utilized; so as to afford any desired voltage or capacity, and wherein the separate units are each readily accessible, and can easily be mounted and dismounted, for examination, repair or replacement.

A further object of this invention is to provide a construction of relative simplicity, for containing as many units as may be needed, and of such a character that it can be built in sections, each of which can be properly attached to one or more other sections of the same sort, and detached when required, with the result that when any part of the assembled device becomes defective or is damaged or impaired, the consequences can be localized and remedied with the least possible expense, labor and difficulty.

Other advantages of my invention are set forth in the following specification, taken with the drawings, showing a preferred form of my invention. The disclosure, however, is illustrative only, and I may resort to variations in structure, not necessarily mentioned herein, but constituting no departure from the principle of my invention, as defined by the broad and general meanings of the terms in which the appended claims are expressed.

On the drawings, Figure 1 is a top plan of a section of a construction according to my invention; and

Figure 2 is a vertical section thereof.

The same numerals identify the same parts throughout.

I show at 1 in Figure 1 a plurality of units, each consisting of a complete condenser, having sheets of conducting material C, separated by sheets of insulation or dielectric D; indicated diagrammatically only on Figure 1. The structure and design of these units are not material to this invention, as the separate condensers may be made up in numerous ways.

I arrange the separate condensers in radial formation, with reference to a common cen-

ter or axis, like the spokes of a wheel, the separate sheets C and D being transverse to the radius extending lengthwise of each unit. Half of the conductive sheets or elements C of each condenser will be connected to a common pole or terminal and joined to a common conductor at the center, while the remaining sheets C of each condenser will be joined to another common conductor at the outer ends of the condensers; so that the condensers thus arranged are in parallel. The manner in which the two sets of conductive elements C of opposite polarity are thus connected, will be apparent to those skilled in this art and need not be particularly illustrated. The entire group of condensers is mounted in a housing consisting of a top plate 2, preferably of metal; and a similar bottom plate 3. These two plates are dished within their peripheries, the bottom plate being inverted; and between the two plates is a tubular part or hollow body 4, of porcelain or other insulation, made fast to the top and bottom plates at its opposite upper and lower ends. Such a housing with a group of radial condensers therein, as described, makes a complete section; and as many of such sections can be employed in the aggregate as one wishes. In Figure 2, I show two such sections, one on top of the other; but a greater number can just as readily be employed, to build the apparatus up to any given height, for increased voltage or greater capacity.

At the center of each section is a head 5, supported by the top 2, as by a threaded stud made fast in the upper end of the head; and passing through a central opening in the plate 2, where it is secured by one or more nuts 7 above the top plate. Adjacent its lower end this head has a number of flat, plane lateral faces 8, against which the separate units or condensers are pressed. I surround the group of radially arranged condensers by a conductor ring 9, and at the adjacent end of each condenser is a thrust plate 10, engaged by a bolt 11. By turning these bolts the condensers are forced into tight engagement with the faces 8 of the head 5, and each bolt can of course be made fast with one or more lock nuts 12 on the outside of the ring 9.

This ring is supported on posts 13, secured to the plate 3 by threaded bolts 14. The portion 4 of the housing has top and bottom flanges 15, and these flanges, and the dished portions of the plates 2 and 3, have openings 16 for fastening bolts 17, which carry nuts 18. Thus the portion 4 and the plates 2 and 3 are affixed together. Between the plates and the part 4 are packing rings or gaskets 19, to seal the joints and enable the housing to be made leak-proof, so that it can be filled with oil or wax.

The circumferential flanges 20 of the plates 2 and 3 enable the different sections to be joined together when more than one is to be employed as in Figure 2; these flanges having alined holes for headed bolts 21 to be engaged at their ends by nuts 22. Owing to the dishing of the plates 2 and 3, the sections will be in direct contact only at their flanges, and a chamber 23 will exist between each two sections, so as to protect each section as much as possible from any heating effects in the adjacent sections.

The inner ends of the condensers 1 of each section are joined to the top plate 2 through the head 5 and the outer ends to the plate 3 through the ring 9 and posts 13, all the parts being of conductive material for the purpose. The condensers of each group are in parallel with each other, but the groups of the different sections are in series by reason of the junc-ture of the top plate 2 of each section with the bottom plate of the next section above. To connect the entire device in circuit, the leads are joined to uppermost plate 2 and lowermost plate 3.

Each section can easily be dismounted, and the top plate 2 removed to obtain access to the condensers 1 therein. Any unit 1 can then readily be taken out for repair, or a new one substituted. For such a purpose the operator need only remove the bolts 21 and 17 and the nut 7, and loosen the bolts 11. And if from any cause the construction should be broken or damaged, or the porcelain 4 be cracked, the injury is confined to one section only, and the loss of contents to the oil or wax therein, the contents of the other sections being effect-ually retained.

The head 5 and the ring 9, between which the condensers are clamped, serve both as supporting means and as terminals for the condensers of each section to connect the condensers to the top 2 and bottom 3 which are closures for the opposite upper and lower ends of each housing or section, as well as terminals; so that when two or more sections are assembled and secured with their flanges 20 in contact, the condensers of one are at once placed in circuit with the condensers of the other or others.

Having described my invention what I believe to be new and desire to secure and pro-

TECT by Letters Patent of the United States is:—

1. A construction comprising a housing, including top and bottom plates separated by insulation, a head supported in the housing by one of said plates and a ring supported in the housing by the other, and a plurality of condensers arranged in radial formation between said head and said ring. 70

2. A construction comprising a housing, including top and bottom plates separated by insulation, a head supported in the housing by one of said plates and a ring supported in the housing by the other, and a plurality of condensers arranged in radial formation 80 between said head and said ring, said head and said ring being of conductive material to serve as terminals for the condenser. 75

3. A construction comprising a housing, including top and bottom plates separated by insulation, a head supported in the housing by one of said plates and a ring supported in the housing by the other, and a plurality of condensers arranged in radial formation 90 between said head and said ring, said plates being of conductive material to enable the condensers to be put in circuit thereby. 85

4. A construction comprising a housing, including top and bottom plates separated by insulation, a head supported in the housing by one of said plates and a ring supported in the housing by the other, and a plurality of condensers arranged in radial formation 95 between said head and said ring, said head and ring being of conductive material to serve 100 as terminals for the condensers, and said plates being of conductive material to enable the condensers to be connected in circuit therethrough.

5. A construction comprising a housing 105 having a hollow body of insulation, closure plates for the ends thereof, a head centrally supported by one of said plates in the housing, said head having plane faces on its periphery, a ring supported by the other plate, in the 110 housing, and a plurality of condensers arranged radially between the head and the ring, and engaging said faces at one end, clamping means abutting the opposite ends of said condensers, and means carried by the 115 ring for adjustably engaging the clamping means.

6. A construction comprising a plurality of sections assembled end to end, each section including a hollow body of insulation, 120 closure plates for the extremities of the body, the closure plates at the meeting ends of the sections being secured together around their edges, one or more condensers in each section, and supporting means in each section, attached to each plate and carrying the condensers between them, said means and said plates being conductive to enable the condensers to be readily connected to an external circuit. 125

7. A construction comprising a housing, including top and bottom plates separated by insulation in the form of a hollow body, a head supported in the body by one of said plates and a ring supported in the body by the other, and a condenser between said head and said ring and encircled by the ring. 5
8. A construction comprising a housing, including top and bottom plates separated by insulation in the form of a hollow body, a head supported in the body by one of said plates and a ring supported in the body by the other, and a condenser between said head and said ring and encircled by the ring, said head and said ring being of conductive material to serve as terminals for the condenser. 10
9. A construction comprising a housing, including top and bottom plates separated by insulation in the form of a hollow body, a head supported in the body by one of said plates and a ring supported in the body by the other, and a condenser between said head and said ring and encircled by the ring, said plates being of conductive material to enable 15 the condenser to be put in circuit thereby. 20
10. A construction comprising a housing, including top and bottom plates separated by insulation in the form of a hollow body, a head supported in the body by one of said plates and a ring supported in the body by the other, and a condenser between said head and said ring and encircled by the ring, said head and ring being of conductive material to serve as terminals for the condenser, and 25 said plates being of conductive material to enable the condenser to be connected in circuit therethrough. 30
11. A condenser adapted for use with high potentials comprising in combination an open ended housing of insulation, metallic closure members for the housing, a condenser stack and a clamp therefor within the housing, the clamp being supported by one of said closure members, the latter also comprising terminals 40 for the condenser. 45
12. A condenser adapted for use with high potentials comprising in combination an open ended housing of insulation, metallic closure members for the housing, a condenser stack and a clamp for exerting pressure thereon within the housing, the stack being spaced from, and the clamp being positioned by, one of the closure members. 50
13. A condenser adapted for high potential use comprising in combination an open ended tubular housing of insulation, metallic plates for closing each end of the housing, a condenser stack and a clamp for compressing and positioning the stack within the housing, the clamp being supported by one of said closure plates. 55
14. A condenser adapted for high potential use comprising in combination an open ended tubular housing of insulation, metallic plates for closing each end of the housing, a con- 60
- denser stack and a clamp for compressing and positioning the stack within the housing, the clamp and stack being spaced from, and the clamp being positioned by, each of said closure plates. 70
15. A condenser adapted for high potential use comprising in combination an open ended tubular housing of insulation, metallic closure plates for the housing, a condenser stack surrounded and compressed by a clamp within the housing, and means for securing the clamp to each of the closure plates to position the assembly within the housing, said closure plates also comprising the terminals of the condenser. 75
16. A condenser adapted for high potential use comprising in combination an open ended tubular housing of insulation, metallic closure plates for the housing, a condenser stack surrounded and compressed by a clamp within the housing, and means for securing the clamp to each of the closure plates and spacing the same therefrom to position the stack intermediate the ends of the housing. 80
17. A condenser adapted for high potential use comprising in combination an open ended tubular housing of insulation, metallic closure plates for the housing, a condenser stack surrounded and compressed by a clamp within the housing, and means for securing the clamp to each of the closure plates in spaced relation therewith to position the stack intermediate the ends of the housing, the stack also being spaced from each of the metallic closure plates, the latter comprising 90 the terminals of the condenser. 95
18. A condenser adapted for high potential outdoor use comprising in combination an open ended porcelain housing, metallic plates for closing the housing with readily removable means for securing the plates thereto, a condenser stack positioned by a clamp for exerting pressure thereon within the housing, means for connecting the clamp to said end plates to secure the clamp in position, the end plates being electrically connected to the stack and comprising the terminals of the condenser. 105
19. A condenser adapted for high potential outdoor use comprising in combination an open ended porcelain tube, metallic plates for closing the tube, a condenser stack positioned by a clamp for exerting pressure thereon within the tube, and means for securing the clamp to said end plates in spaced relation to position the stack midway between the end plates and spaced from the inner wall of the tube, said end plates comprising the terminals of the condenser. 115
20. A condenser comprising in combination an open ended housing of insulation, metallic closure members for the housing, a condenser stack positioned between clamping members within the housing, each of the clamping members being supported by one 120
- 125

of said closure members respectively, the clamping member's mutually cooperating to apply pressure to the stack.

means for mounting the device and for mechanically and electrically connecting the device in series with similar devices.

In testimony whereof I affix my signature.

WILLIAM DUBILIER. 70

21. A condenser unit comprising in combination a cylindrical porcelain housing, a condenser body within the housing, a dish-shaped metal closure plate secured to one end of the housing to form the bottom and having its concave surface disposed outwardly so that the rim of the plate comprises a stable base for the unit, another dish-shaped metal plate secured to the other end of the housing to form the top and having its concave surface disposed outwardly so that the rim comprises a stable mounting means to support the base of a similar condenser unit, said metal plates forming the terminals of the condenser whereby two or more units may be stacked to form a self supporting column of condensers in series.

22. A high tension electrical condenser comprising a sheet stack consisting of a plurality of stack elements arranged in series, a casing of insulating material surrounding and enclosing said stack, a clamping device disposed within said insulating casing and engaging the ends of said stack, metal end structures closing said insulating casing and forming terminals for the condenser, said end structures having continuous flanges extending out and beyond said insulating casing and forming means for mounting the condenser and electrically connecting the same in series with similar condensers.

23. A high tension electrical condenser comprising a sheet stack consisting of a plurality of stack elements arranged in series, a casing of insulating material surrounding and enclosing said stack, a clamping device disposed within said insulating casing and having separate parts engaging the respective ends of said stack, and metal end structures closing said insulating casing and forming terminals for the condenser.

24. A high tension electrical condenser comprising a plurality of serially arranged elements forming a condenser stack, means for clamping said stack and applying pressure thereto, a tubular insulating casing surrounding said stack and clamping means, a metal closure at one end of said insulating casing to which one side of the clamping means is secured, said closure forming one terminal of the condenser, and another metal closure at the other end of said casing forming the other terminal for the condenser.

25. A high tension electrical device comprising a plurality of serially positioned electrical units forming a flat sheet stack, a tubular casing of insulating material surrounding said stack, metal structures secured to opposite ends of said casing and connected to opposite ends of the stack, and continuous flanges on said metal end structures forming
